MATERIAL HANDLING PALLET

William F. Weitzel, Baltimore, Md., assignor to
Western Electric Company, Incorporated, New
York, N. Y., a corporation of New York

Application October 6, 1948, Serial No. 53,024

4 Claims. (Cl. 248—120)

1

This invention relates to material handling pallets, and more particularly to pallets adapted to be stacked or otherwise handled by industrial fork lift trucks.

Pallets generally are used to enable industrial fork trucks to lift, store, handle and transport a plurality of articles or packages in a manufacturing plant. Storing loaded pallets in stacks or tiers usually requires double-faced pallets having top and bottom decks so as to maintain perpendicular stacks or tiers.

In order to use an industrial lift fork truck having load-bearing wheels positioned directly under the load to be lifted, the present type of double-faced pallets makes it necessary for the structure carrying the load wheels to straddle the pallet, in which case, the structure on which the load-bearing wheels are mounted is substantially wider than the main body of the truck. It is desirable to have the structure carrying the load-bearing wheels about the same width as the body of the truck to obtain maximum maneuverability of the truck in its travel about the factory floor.

An object of the invention is to provide new and improved material handling pallets.

Another object of the invention is to provide new and improved double-faced pallets capable of being used with industrial fork trucks having load-bearing wheels positioned under the load.

A pallet embodying certain features of the invention comprises a top deck on which the material to be handled is positioned and a bottom deck parallel to the top deck and having longitudinal passageways therein to receive the load-bearing wheels of a fork truck.

A clear understanding of the invention may be had from the following detailed description of a specific embodiment thereof, when read in conjunction with the appended drawing, in which:

Fig. 1 is a side elevation of an industrial fork truck positioned in operating relationship with a pallet embodying the invention;

Fig. 2 is a perspective view of a pallet constructed in accordance with the invention;

Fig. 3 is a fragmentary, sectional view taken along line 3—3 of Fig. 2, and

Fig. 4 is a fragmentary, horizontal section taken along line 4—4 of Fig. 1.

Referring now to the drawing and more particularly to Fig. 1, there is shown a pallet 10, which comprises a channel-shaped member 11 formed from corrugated sheet metal to provide a corrugated upper deck 12 having marginal legs 13—13 extending downwardly therefrom. A channel-shaped member 15 formed from cor-

2

rugated sheet metal to provide a lower deck surface 16 having marginal legs 17—17 of equal length extending upwardly therefrom to engage the under surface of the upper deck 12. The width of the lower member 15 is substantially less than that of the upper member 11, and the lower member 15 is centrally positioned beneath the upper member 12 which leaves a longitudinal opening between each pair of adjacent legs 13 and 17. The legs 17—17 of the lower member 15 have cutouts 18—18 spaced therealong to receive the corrugations of the upper deck 12. The lower member 15 is welded to the upper member 11 along the junction surface between the outside surface of the legs 17—17 and the under surface of the upper member 12 to form a rigid, box-like constructed pallet. Z members 20—20 (Fig. 2), which are formed from flat sheet metal, are positioned at each side of the upper member 11, each with an upper horizontal leg 21 engaging the under side of the upper deck 12 and the end of the adjacent leg 17. Cutouts 19—19 are provided in the horizontal leg 21 to receive the corrugations of the deck 12. The lower horizontal legs 22—22 of the Z members 20—20 lie in the same horizontal plane as the lower deck 16, and have an upturned flange 23 formed integrally therewith which engages the lower end of the adjacent leg 13 of the upper member. The leg 22 and the flange 23 of each of the members 20—20, serve to enclose the bottom edges of the legs 13—13 and thereby prevent the edges from injuring persons handling the pallet 10. The Z members 20—20 are welded to the upper member 11 along the flange 23 and to the under surface of the upper deck 12 along the horizontal leg 21. In addition to these surfaces which are welded together, it may be desired to weld all other surfaces of the members that are in engagement which are accessible to the welding rod, electrode, or the like.

The upper member 11 (Fig. 3) is formed so that its corrugations extend downwardly toward the lower member from the deck surface 12, while the lower member 15 is formed so that its corrugations extend upwardly toward the upper member from its deck surface 16, as shown in Fig. 3. The cutouts 18—18 in the legs 17—17 and the cutouts 19—19 in the upper horizontal legs 21—21 of the Z members 20—20 permit the legs in each case, to engage the flat portions of the upper member 11. Since the legs 17—17 of the lower member 15 are of equal length, and since the lower horizontal portion of the Z members lie in the same plane as the lower deck 16,

3 the deck 16 and legs 22-22 all are parallel to the upper deck 12.

The lower member 15 (Fig. 2) and the Z members 20-20 are designed to fit on the upper member 11 to form longitudinal passageways 24-24 equidistantly positioned astride the central axis of the pallet 10 and an opening 25 between the upper and lower deck members and intermediate the passageways 24-24. If desired, a channel 26 may be welded in position in the opening 25 between the upper deck 12 and the lower deck 16 and equidistantly between the passageways 24-24 for the purpose of supporting the central portion of the upper deck 12 whereby the pallet 10 is capable of supporting heavy loads. This type of construction produces what is commonly referred to as a "double-face pallet" which is used generally to store articles, such as the articles 26-26, in stacks, such as the stack indicated generally at 27 (Fig. 1). There is shown in Fig. 1 a particular type of industrial lift fork truck indicated generally at 30, which may be used for lifting and transporting pallets, such as the pallet 10, loaded with a plurality of articles and for storing the articles in stacks, such as the stack 27. The general construction and operation of industrial trucks of this type are well known, hence the truck 30 will be described only in so far as it is necessary to illustrate clearly certain features of the present invention.

The truck 30 (Fig. 1) is provided with a vertical mast 31 secured to one end of a structural body 32. A pair of forks 33-33 are secured to a carriage 34, which is slidably positioned on the mast 31. A swivel wheel 37 is provided on the other end of the body 32 of the truck, and is arranged to be controlled by a handle 38 so as to guide the truck in its path of travel. A pair of arms 40-40 are secured to the body 32 of the truck adjacent to the mast 31 and extend forwardly therefrom. A load bearing wheel 41 is suitably mounted in a bearing provided on the end of each arm 40. The wheels 41-41 are relatively small in diameter so that each arm 40 and its respective wheel 41 may be positioned under a pallet on which a plurality of articles rest. The arms 40-40 on which the load-bearing wheels 41-41 are mounted are flush with the sides of the body 32 of the truck so that the truck has a uniform width throughout its entire length.

By mounting the load-bearing wheels 41-41 of the truck 30 on the ends of their respective forwardly extending arms 40-40, the load capacity of trucks like the truck 30 is increased approximately 100% over the load capacity of conventional types of industrial trucks which have their load-bearing wheels mounted directly under the vertical mast, like the mast 31 of the truck 30. However, the arrangement of the load-bearing wheels of the truck 30 prevents its use with conventional double-faced pallets, unless the pallet is of such width that the arms 40-40 can straddle it. Under such conditions, the load that could be carried on such a narrow pallet would prevent the utilization of the maximum load capacity of the truck.

The double-faced pallet 10, shown in Fig. 2, was designed primarily for use with industrial fork trucks like the truck 30 so that the arms 40-40 and the wheels 41-41 may be positioned in the passageways 24-24, under the top deck of the pallet and yet not interfere with the lifting of the pallet when the forks 33-33 are raised. In using pallets, like the pallet 10, for purposes of transporting a plurality of articles 26-26 by

means of the fork lift truck 30 and more particularly for storing a plurality of articles in a stack 27, the pallet 10 is placed on the factory floor and loaded with a suitable number of articles 5 26-26, which are indicated as group "A." The truck 30 then is positioned in front of the pallet 10 so that the arms 40-40, which carry the wheels 41-41 are in line with the openings 24-24 of the pallet. The truck 30 is moved toward 10 the pallet to cause the wheels 41-41 and the arms 40-40 to enter their respective passageways 24-24 (Figs. 1 and 4), and the forks 33-33 enter the opening 25 between the upper member 11 and the lower member 15 so that they straddle the central channel 26.

The power means provided on the truck is then actuated to raise the forks 33-33 (Fig. 1) which, in so doing, engage the under side of the upper deck 12 and lift the pallet 10 and group "A" of 20 articles 26-26 positioned thereon off the factory floor. The truck 30 then is driven to the point at which the "A" articles are to be stored and the operating mechanism for the forks is actuated to lower the loaded pallet 10 to the floor. 25 This disposition of the group "A" articles on the factory floor is the initial step on the formation of the stack 27. The truck 30 picks up a second pallet 10 loaded with articles 26-26, designated as group "B," and deposits them on top of group 30 "A" in the further formation of stack 27. A third pallet loaded with articles 26-26, which are designated group "C" (Fig. 1), is picked up by the truck in the same manner and deposited on the group "B" of the stack 27. In depositing 35 article groups "B" and "C" successively on the stack 27, the load-bearing wheels and arms of the truck are run in the passageways 24-24 of the bottom pallet 10.

It may be desirable in some cases, where the 40 weight of the articles being handled permits it, to carry several loaded pallets on the truck at a time. In which case, a second pallet 10 is placed on top of the group "A" articles 26-26 loaded on the bottom pallet and loaded with a predetermined number of the articles 26-26, such as those which have been designated as the group 45 "B" articles of stack 27 (Fig. 1).

The truck 30 may be positioned so that the 50 forks 33-33 engage the pallet 10 carrying the group "A" articles in the manner described hereinabove. When the forks are raised, group "A" and "B" articles are lifted from the floor and thereafter may be transported together to the storage point and deposited to form a portion 55 of the stack 27. In either case, the pallet 10, by being a double-faced pallet having the passageways 24-24 adjacent to the longitudinal extremities of the lower deck thereof, permits the use of fork trucks like the truck 30, and at the same time permits storage of articles in stacks, such as the stack 27.

While the pallet 10 has been described as being 60 adapted particularly for use with industrial fork trucks having load-bearing wheels positioned directly under the load, the pallet may be used with other types of industrial fork trucks, such as the conventional counterweight type of fork truck, and for all purposes where either single-faced or double-faced pallets are required.

It is to be understood that while the pallet 10 has been described in the preferred embodiment of the invention as being formed from corrugated metal sheets, various portions thereof could be formed from flat metal sheets to produce a pallet 70 capable of supporting heavy loads, or the entire

pallet could be fabricated from wood without departing from the spirit and scope of the invention.

What is claimed is:

1. A pallet for use with fork lift trucks having load-bearing wheels positioned under the lifting forks, which comprises an upper deck member having longitudinally extending marginal flanges projecting perpendicularly downward therefrom, a lower deck member having longitudinally extending marginal flanges projecting perpendicularly upwardly therefrom and secured to the upper deck member so that the portion between its marginal flanges is spacedly positioned parallel to said upper deck, said bottom deck being substantially narrower than the upper deck and centrally positioned so that it forms a longitudinal groove between its marginal flanges and the corresponding flanges of the upper deck, and a pair of Z members, one secured to each marginal flange of the upper deck members so as to form a longitudinal passageway between the Z member and the adjacent marginal flange of the lower deck, said longitudinal passageways being designed to receive the load-bearing wheels of the truck when the forks of the truck are positioned between the upper and lower deck members.

2. A pallet for use with fork lift trucks having load-bearing wheels positioned under the lifting forks, which comprises a channel-shaped upper member having the long side thereof positioned horizontally to form a horizontal upper deck of the pallet and having its marginal flanges extending vertically downwardly, a channel-shaped lower member secured in an inverted position inside the vertical flanges of the upper member so that its flat portion is spacedly positioned parallel to the horizontal deck of said upper member, and a Z member positioned adjacent to each vertical flange of the upper member so as to form a longitudinal passageway between the vertical flange of the lower member and the Z member, said Z members having upturned flanges provided along one side thereof which engages the outer surface of the vertical flanges of the upper channel-shaped member, whereby the upper and lower members form a rigid, double-faced pallet having a longitudinal passageway at each extremity of the lower deck for receiving the load-bearing wheels of the truck.

3. A pallet for use with fork lift trucks having load-bearing wheels positioned under the lifting forks, which comprises a channel-shaped upper member having the long side thereof positioned horizontally to form the upper deck of the pallet and having its perpendicular marginal flanges extending downwardly therefrom, a channel-shaped lower member secured in an inverted position inside the vertical flanges of the upper member so that its long side is spacedly positioned parallel to the horizontal side of said upper member, a Z member positioned adjacent to each flange of the upper member so that it forms

a longitudinal passageway between the vertical flange of the lower member and the said Z member, said Z members having an upturned flange provided along one side thereof which engages the outer surface of the adjacent vertical flange of the upper member, and a channel-shaped bracing member positioned equidistantly between said passageways so as to engage the parallel portions of the upper and lower deck members.

10 4. A double-faced pallet for use with industrial fork lift trucks having load-bearing wheels positioned under their load engaging forks, which comprises an upper deck member formed of corrugated metal to provide a rectangular top deck having perpendicular flanges formed integrally therewith and extending downwardly therefrom, a bottom deck member formed of corrugated metal so as to provide a rectangular lower deck having perpendicular flanges formed integrally therewith, said bottom deck member secured to the upper member in an inverted position between the flanges of the upper member, whereby the flanges thereof engage the upper deck and spacedly position the lower deck parallel to the upper deck member, said lower channel-shaped member being substantially narrower than said upper member and centrally positioned between the marginal flanges thereof so as to form an elongated opening between each flange of the lower deck and the adjacent flange of the upper deck, a Z member positioned in each opening so that the parallel flanges thereof engage the upper deck member and the edge of the marginal flanges thereof, respectively, said Z members 30 forming longitudinal passageways between the flanges of the lower members and the said Z members, the lower horizontal flange of each Z member being in the same plane as that of the lower deck and having an upturned flange 35 formed thereon which engages the outer surface of the adjacent flange of the upper member, and a channel-shaped member positioned equidistantly between said longitudinal passageways for supporting the portion of the upper deck between said passageways, whereby when such a lift truck is positioned to pick up the pallet, the forks enter the opening between the upper and lower decks and the load-bearing wheels enter the longitudinal passageways adjacent to the lower deck.

WILLIAM F. WEITZEL.
